EXTENSIBLE PAINT ROLLER CORE

Frank W. Gill, 941 Baker St., Wisconsin Rapids, Wis.

Filed Mar. 18, 1958, Ser. No. 722,291

9 Claims. (Cl. 29—110)

This invention relates to an extensible paint roller core.

Paint rollers comprise a spindle provided with a handle and upon which a core is rotatably mounted for the support of an applicator sleeve frequently made of lambswool or of synthetic wool.

Paint rollers of different lengths are used in different situations. The present invention makes it possible to adjust the core to receive a standard sleeve of either of a number of different lengths, thus avoiding any unnecessary duplication of the core and its mounting.

In accordance with the invention, a core of dimensions suited to receive the shorter applicator sleeve is rotatably mounted on the spindle of the device, and an extension supported in part on the shorter core and in part on the spindle itself is reciprocable to and from a retracted position in which the extension is housed within the dimensions of the contracted core. When the extension is advanced from such housed position, it cooperates with the original core to support the longer applicator sleeve. These results are achieved by constructing the basic core of a pair of collars individually journaled upon the spindle and connected by diametrically opposite spring ribbons. The collar at the outer end of the spindle has slots angularly offset from the ribbons of the basic core to receive spring ribbons which carry a collar constituting the end of the extensible core. These ribbons reciprocate through the slots and are formed for rotative interlocking engagement with the slotted collar to retain the extensible core in its operative use.

In the drawings:

Fig. 1 is a view partially in side elevation and partially in axial section showing a device embodying the invention, the basic core and extension core being shown in section, and the latter being illustrated in its extended position of use in full lines, and being shown in dotted lines in its retracted position.

Fig. 2 is a view in perspective on an enlarged scale showing the device illustrated in Fig. 1.

Fig. 3 is a view taken in section on the line 3—3 of Fig. 1, the parts being shown on an enlarged scale.

Fig. 4 is a view on the line 4—4 of Fig. 3.

The spindle 5 comprises a piece of heavy wire having an integral handle 6 provided with a grip 7 in accordance with conventional practice. The basic core rotatable on the spindle comprises a cup-shaped collar 8 having hub portion 9 and a like collar 10 having a hub portion 11. The collars 8 and 10 are inter-connected by outwardly bowed straps or ribbons of spring steel as indicated at 12, these desirably being riveted to the respective collars. The collars are confined against axial displacement on the spindle by any desired means, as by the slight deformations of the spindle at 13 and 14.

For the purposes of the present invention, the generally radial sheet metal wall 15 of the collar 10 which is outermost on the spindle is provided with slots at 3 and 4 through which slidably project the straps 16, 17

2

which support an auxiliary collar 18 similar to the collars 8 and 10 except that it lacks the hub with which collars 8 and 10 are respectively provided. The spring steel straps 16, 17 constitute the ends of a band which is folded upon itself at 19 and 20 to form a transverse portion 21 constituting a bearing part apertured at 22 for sliding engagement with the spindle 5. Like the straps 12, the portions 23, 24 of straps 16, 17 are slightly bowed outwardly. They both have reverse bends at 25, 10 26, forming intervening radial portions 27 which, in 15 the extended position of collar 18, are seated within collar 10.

The collars 8 and 10 and straps 12 constitute first core means. Collar 18 and straps 16 and 17 constitute an extension core means movable between the retracted dotted line position of Fig. 1 and the extended position of Fig. 2.

Opposite margins of the relatively straight terminal portions of the straps 16 and 17 are notched at 28, 29 20 respectively for interlocking engagement with the radial wall portion 15 of collar 10 adjacent the slots 3, 4, as clearly appears in Figs. 2, 3 and 4. The dimensions of the slots are such that the spring straps 16, 17 are readily disengaged from such interlocking engagement 25 with wall 15 by relative rotation of the straps and their connecting strap 21 about the axis of the spindle 5. Upon such disengagement, the strap portions 16, 17 are movable through the slots 3 and 4 to the nested or retracted positions of the parts shown in dotted lines in 30 Fig. 1.

In this retracted position of the extensible portions of the apparatus, the shorter of two conventional applicator sleeves (not shown) will just cover all three of collars 8, 10 and 18. For example, a conventional sleeve 35 of seven inches in length might be assumed to be the sleeve under consideration.

When the shorter sleeve is in use, it will provide virtually continuous support from the several collars and for intervening and convexly bowed resilient straps 12, 40 16 and 17.

If the extensible parts are withdrawn to the position shown in Fig. 2 and rotated to interlock the spring straps 16, 17 with collar 10, as there illustrated, the device will accommodate a longer applicator sleeve, as 45 for example, a conventional nine inch sleeve. Such a sleeve will be supported at its ends on collars 8 and 18 and will have intermediate support from the several flexible ribbons and the intermediate collar 10. Throughout most of the length of the longer sleeve, it 50 will be supported on four ribbons, but adjacent the collar 8 and adjacent the collar 18 it will be supported by two ribbons only. Nevertheless, the support is entirely adequate to enable the applicator sleeve to perform its intended function.

55 I claim:

1. In a device of the character described for supporting paint roller applicator sleeves of differing lengths, the combination with a spindle, of a first sleeve supporting core means rotatably mounted on the spindle and an extension sleeve supporting core means having means supporting it on the spindle and on the first core means for sliding axially of the spindle between a sleeve supporting retracted position on the spindle respecting the first core means and a sleeve supporting extended position on the 60 spindle with respect thereto.

2. The device of claim 1 in which the extension core means has a spindle bearing part through which the spindle extends, and which is axially adjustable along the spindle in the movement of the extension core means between its retracted and extended positions.

70 3. The device of claim 2 in which the first core means comprises a skeletonized structure having collars spaced

axially of the spindle and means extending between said collars for the support of an applicator sleeve.

4. The device of claim 3 in which said extension core means comprises a third collar free of direct contact with the spindle and a pair of diametrically opposite bands for which a collar of the first core means provides guide openings, said bearing means connecting said bands and being apertured to receive a portion of the spindle intermediate the ends of the first core means.

5. The device of claim 4 in which said bands and the apertured collar are respectively formed for inter-locking engagement upon relative rotation in the extended position of the extension core means.

6. In a device of the character described for supporting various paint roller applicator sleeves of differing lengths, the combination with a spindle, of a first core means rotatably mounted thereon and comprising axially spaced collars and outwardly bowed bands having their ends respectively connected with said collars and disposed at different sides of the spindle, the collar nearest the end of the spindle being provided with a generally radial wall having slots angularly offset from said bands, and an extension core means comprising a band having a central portion provided with an aperture reciprocable upon the spindle between the collars of the first core means, and leg portions extending from said central portion in general parallelism with the spindle and projecting through said slots beyond the end of the spindle, and a third collar connecting the projecting ends of said leg portions, and movable therewith between a retracted position of proximity to the slotted collar and an advanced position remote therefrom.

7. The device of claim 6 in which said legs have notches interlockably engageable with the slotted wall

through which they extend when rotated respecting said wall in the extended position of said third collar.

8. In a paint roller core for supporting applicator sleeves of different lengths, a spindle having a handle and a free end, a first core including a pair of collars individually journalled on the spindle and outwardly bowed spring bands extending between the collars on opposite sides of the spindle, and a second and extensible core including a third collar free from direct contact with the spindle and a band folded on itself and providing a bearing through which the spindle extends and providing outwardly bowed portions extending for a portion of the length between the collars of the first core, portions of the second core band and the collar thereof projecting beyond the first core collar adjacent the end of the spindle when the second core is extended, the bowed portions of the second core band extending along opposite sides of the spindle at substantially 90° from the first core bands.
9. The device of claim 8 in which the first core collar adjacent the end of the spindle has slots and the band of the second core moves through the slots and is supported therein upon extension of the second core, the second core band having notches severally engageable with said first core collar for interlocking the cores against undesired axial movement.
